US00D921728S

(12) **United States Design Patent** (10) **Patent No.:** **US D921,728 S**
(45) **Date of Patent:** ** *Jun. 8, 2021

(54) **PACKAGING MACHINE**

(71) Applicant: **BOBST MEX SA**, Mex (CH)

(72) Inventor: **Antonio Longo**, Prilly (CH)

(73) Assignee: **BOBST MEX SA**, Mex (CH)

(*) Notice: This patent is subject to a terminal disclaimer.

(**) Term: **15 Years**

(21) Appl. No.: **29/691,178**

(22) Filed: **May 14, 2019**

(30) **Foreign Application Priority Data**

Nov. 15, 2018 (WO) 9673901

(57) **CLAIM**

The ornamental design for a packaging machine, as shown and described.

DESCRIPTION

The patent or application file contains at least one drawing executed in color. Copies of this patent or patent application publication with color drawing(s) will be provided by the Office upon request and payment of the necessary fee.

FIG. 1 is a right perspective view of the packaging machine;

FIG. 2 is a front view thereof;

FIG. 3 is a back view thereof;

FIG. 4 is a top view thereof;

FIG. 5 is a bottom view thereof;

FIG. 6 is a left side view thereof; and

FIG. 7 is a right side view thereof.

FIG. 8 is a right perspective view of the packaging machine of FIGS. 1-7 with certain features shown in red and grey; and

FIG. 9 is a front view thereof.

FIG. 10 is a right perspective view of the packaging machine of FIGS. 1-7 with certain features shown in red; and,

FIG. 11 is a front view thereof.

The broken lines depict environmental structure that form no part of the claimed design. In FIGS. 8-9, the claimed design is shown with, and includes, grey and red coloring. In FIGS. 10-11, the claimed design is shown with, and includes, red coloring.
